HOLDER FOR SHARPENING EDGED TOOLS
Arland J. Tidwell, 1185 North 50 East,
Orem, Utah 84057
Filed Apr. 13, 1966, Ser. No. 542,253
2 Claims. (Cl. 51—219)

ABSTRACT OF THE DISCLOSURE

Apparatus for holding a drill bit while it is being sharpened on a grinding wheel. The apparatus includes a plate with a groove in its top surface in which the drill bit is clamped. A finger extends from the underside of the plate toward the grinding wheel and cooperates with the underside of the plate to envelop the outer edge of the tool rest on the grinder. Using this finger, the apparatus is pivoted on the outer edge of the tool rest in such a manner as to guide the point of drill bit over the grinding wheel to sharpen the cutting edge and give the drill bit point its desired rake angle.

This invention relates to a holder for drill bits that maintains the drill bit in proper alignment relative to the surface of a grinding wheel, while the point of the bit is being ground.

In the past, holders for grinding drill bits have been complex and awkward to use. They have usually comprised a complicated apparatus that is both expensive in its initial cost and requires valuable labor time to set it up before it can be used to grind drill bits.

The object of my invention is to provide a simple, inexpensive device for holding a drill bit while it is being sharpened on a bench grinder. My invention is designed to enable the operator to obtain a properly ground drill point with a minimum amount of effort during both the set-up and the grinding operations.

In its present preferred form, my holder comprises a flat plate with a groove in its top surface, and a simple clamp means for holding the drill bit within this groove. A finger extends from the bottom surface of the plate and is bent towards one end of the plate. While the point of the drill bit is being ground, the plate is rotated up and down, using the tool rest of the bench grinder as a fulcrum. The tool rest is inserted in a pocket formed by the bent finger and the bottom surface of the plate.

The embodiment of my holder disclosed herein is also easily adjustable for use in grinding other tools, such as cold chisels, lathe tools, plane irons, and rotary mower spokeshaves. The use of my holder for these purposes is shown and described in my co-pending United States application, Ser. No. 516,921, filed Dec. 28, 1965, now abandoned.

A complete understanding of the invention may be obtained from the following detailed description and the attached drawings, in which:

FIGURE 1 is a plan view of my holder showing a drill bit clamped thereon;

FIGURE 2 is a side view of the holder of FIGURE 1;

FIGURE 3 is a side view of the holder and drill bit of FIGURE 1 in use on a conventional bench grinder; and

FIGURE 4 is a front end view of the point of a drill bit, illustrating the surfaces that are being ground during the use of my holder.

The drill bit holder 2, shown from the top in FIGURE 1, comprises an elongated flat base plate 4 and an adjustable clamping head 6 that is secured to the plate 4 by a wing bolt 8. V-groove 10 in the top surface of the plate 4 extends diagonally across the plate and beneath the free end of the clamping head 6.

As may be seen in FIGURE 2, this free end of the

2

clamping head 6 is spaced from the top surface of the plate 4 and has two wing bolts 12 which are threaded into the head 6. The wing bolts 12 extend downwardly onto the top of a drill bit D that rests in the groove 10. The 5 drill bit D is held stationary in the groove 10 by tightening the wing bolts 12. The drill bit D is positioned in the groove 10 so that its "point" P extends beyond the end of plate 4 and into contact with the stone S of grinder G, which is shown in its entirety in FIGURE 3.

The "point" of the drill bit is actually a pair of surfaces on the front end of the bit, as illustrated by the point P in FIGURE 4. One edge of each surface of the point P is a cutting lip L, and the cutting lips L do the main cutting of the hole as the drill is advanced through the workpiece. In grinding each surface of the point P, the lip L should be parallel with the grinding surface of the stone S. To obtain this condition, the V-groove 10 housing the drill bit D is positioned at an angle with the grinding surface of the stone S that is complementary to the point angle N of the drill bit (FIGURE 1).

As shown in FIGURE 2, a finger 14 extends downwardly from the bottom surface of the plate 4 and toward the same end of the plate beyond which the point of the drill bit extends. The finger 14 has a concave surface 16 facing the bottom surface of plate 4. The surface 16 and the bottom surface of the plate 4 form a pocket 18 that is adapted to engage slidably the outer edge of tool rest R of bench grinder G, as shown in FIGURE 3.

The finger 14 and pocket 18 extend transversely across the underside of plate 4. Finger 14 is positioned so that the lines along which the sides of the pocket 18 engage the tool rest R are parallel to one cutting lip of point P on drill bit D. Thus, in the manufacture of the holder 2, the angle between the V-groove 10 and the line 19 at the base of pocket 18 is made complementary to the point angle of the drill bit.

In the use of the drill bit holder 2, the bit D is placed in the V-groove 10 as shown in FIGURES 1 and 2. The holder is then placed next to the stone S of grinder G, with the outer edge tool rest R in sliding engagement with the sides of the pocket 18. With the holder 2 held approximately in the solid line position shown in FIGURE 3, the drill bit D is then moved forward in the V-groove 10 until its point P contacts the grinding stone S. The wing bolts 12 are then tightened against the bit D to hold it stationary in the groove 10, and the grinder G is turned on.

The point P is ground by rotating the holder 2 back and forth between the solid-line and dotted-line positions of the holder 2, as indicated by arrows X in FIGURE 3. The outer end of the tool rest R acts as a sliding fulcrum during this rotation, with the concave surface 16 of the finger 14 and the bottom surface of plate 4 sliding in opposite directions over the upper and lower corners of the rest R. As a result of this movement of the holder 2, the point P of the bit D is given short, back-and-forth, grinding strokes against the grinding stone S.

This grinding is repeated on the other surface of point P, and as a result, the cutting lips L (FIGURE 4) are sharpened. In addition, the motion of the drill bit D, caused by the back-and-forth rotation of holder 2 on rest R, grinds the point P to its proper rake angle.

The rake angle of the drill point P is the angle by which the surface of the point slopes away from the cutting lip and thus departs from a true conical surface. The rake angle of the drill point is very critical, since a too-small rake angle will cause too much friction between the drill point and the bottom of the hole that is being cut, and a rake angle that is too large will impose too great a stress on the part of the drill bit around the cutting lip. Either of these conditions can severely damage the drill bit. Thus,

it is a significant advantage that the drill bit holder I have disclosed is simple in construction, yet enables the operator grinding the drill point to obtain a proper rake angle with a minimum of effort.

The holder 2 may be used without the clamping member 6, if the operator desires to hold the bit D in the groove 10 with his hand. However, the operator must be careful to hold the bit firmly while grinding, or else the force of the grinding stone against the bit will cause the bit to fly off the holder 2, and possibly injure someone.

The holder 2 is also capable of being adjusted for use in grinding other tools. By loosening the wing bolt 8, the clamping head 6 may be rotated about the bolt 8 to a number of different positions for holding various types of tools. Marks 20 and 21 (FIGURE 1) are provided on the clamping head 6 and are designed to be matched with various marks on the plate 4. When the marks 20 and 21 are matched with marks d on plate 4, as illustrated in FIGURE 1, the clamping head 6 is in a proper position for holding the drill bit D. Matching the mark 20 with mark a puts the rear of head 6 in proper position for holding cold chisels. Similarly, matching mark 20 with mark b positions the head 6 for holding plane irons, lathe tools, or wood chisels, and matching mark 20 with mark c positions the head 6 for holding rotary lawn mower spoke-shaves. Scribed guide lines 22 are provided on the rear of plate 4 to aid in properly orientating these tools with respect to the grinding surface of the grinding stone S.

Ribs 23 are provided on the bottom side of plate 4 in back of finger 14. These ribs extend transversely across the plate 4, and when a tool other than a drill bit is being ground, the holder 2 is placed on the tool rest R with the outer edge of the rest housed in the dihedral angle 24 between the ribs 23. The manipulation of the holder 2 when held on the tool rest R in this position is shown and described in my co-pending U.S. Patent application, Ser. No. 516,921, filed Dec. 28, 1965.

While one embodiment of my invention has been shown and described herein, other modifications will be readily apparent that are within the scope of the appended claims.

I claim:

- 5 1. Apparatus for grinding the point and sharpening the cutting lip of a drill bit on a grinding stone equipped with a tool rest, said apparatus comprising an elongated plate, means on one side of said plate for holding a drill bit with its point extending beyond an end of said plate, and a finger 10 extending from the other side of said plate and gradually curving toward said end of the plate beyond which the point of said drill bit extends, said finger having an arcuate concave surface facing said other side of said plate, said finger and said other side of the plate enveloping and slidably engaging the outer edge of said tool rest so as to stroke against said grinding stone the point of a drill bit held by said holding means and grind said point to a desired rake angle, and said finger having a width extending transversely across said plate such that said pivoting of 15 said finger and said other side of said plate about said tool rest has a rotational axis parallel to the cutting lip of said drill bit when held by said bit holding means.

- 20 2. Apparatus of claim 1 in which said plate has a groove in one side of said plate, the walls of said groove forming a part of said means for holding said drill bit, said apparatus also including a clamp member mounted on said plate for securing said drill bit in a fixed position in said groove.
